CLAIM

The ornamental design for an automated teller service center enclosure, substantially as shown and described.

DESCRIPTION

FIG. 1 is a front and left side perspective view of an automated teller service center enclosure showing my new design;

FIG. 2 is a front elevational view thereof;

FIG. 3 is a left side elevational view thereof;

FIG. 4 is a right side elevational view thereof;

FIG. 5 is a top plan view thereof; and

FIG. 6 is a bottom plan view thereof.

The broken line showing of a portion of a wall in FIG. 3 is illustrative of environmental structure only. The broken lines appearing in FIGS. 1 and 2 represent an automated teller machine which may be mounted in the enclosure and are not part of the claimed design. The rear of the claimed design is flat.

FIG. 1.

FIG. 5.

FIG. 3.

FIG. 2.

FIG. 4.

FIG. 6.
